LEROY L. RICHARD, OF COALINGA, CALIFORNIA, ASSIGNOR OF ONE-HALF TO SAMUEL ALLEN GUIBERSON, JR., OF SAN FRANCISCO, CALIFORNIA.

WELL-BAILER.

1,160,654.

Specification of Letters Patent.

Patented Nov. 16, 1915.

Application filed December 24, 1914. Serial No. 878,837.

To all whom it may concern:

Be it known that I, LEROY L. RICHARD, a citizen of the United States, residing at Coalinga, in the county of Fresno and State 5 of California, have invented certain new and useful Improvements in Well-Bailers, of which the following is a specification.

My invention relates to that class of well-bailers in which a pipe, cylinder or barrel is 10 provided at its foot or bottom with an admission check valve and a dart in connection therewith, to control the entrance, retention and discharge of the material to be bailed.

The object of my invention is to provide a 15 simple and effective bailer of this class; and to this end my invention consists in the novel well-bailer which I shall hereinafter fully describe by reference to the accompanying drawings, in which—

20 Figure 1 is an elevation of my well-bailer, the barrel being broken. Fig. 2 is a vertical sectional view, enlarged, of the lower end or bottom of the same. Fig. 3 is a cross section on the line $x-x$ of Fig. 2. Fig. 4 is a cross 25 section on the line $y-y$ of Fig. 2. Fig. 5 is a bottom view of the bailer.

1 is the body-pipe, cylinder or barrel of the bailer having at its top the bail or link 2 for the attachment of the sand-line. To the 30 lower end of the pipe or barrel 1 is fitted in any suitable manner the hollow stock or shell 3 of the bailer-bottom. It is here shown as being screwed in at 4 up to a shoulder 5. The stock 3 at its lower end lies below the 35 barrel 1 and this portion is concaved to form a shoe 6 which may assist in cutting into and loosening up the sand. It also serves to better direct the sand into the bailer. The stock 3 is formed on its inside with a seat 7 40 for a ball-valve 8.

9 is the sand-dart. This may assume any form adapted to penetrate the sand and by rotation on its axis to loosen said sand. In its best form the dart is, as here shown, a 45 short section of an auger. The stem 10 of the dart passes through and slides freely in the ball-valve 8. The amount of this movement is defined on the up stroke by a shoulder 11 on the stem, which forms a close 50 joint in a corresponding seat 12 in the bottom of the ball-valve, and on the down movement by a shoulder 13 on the stem which forms a close joint in a corresponding seat 14 in the top of the ball-valve. For 55 constructive purposes the upper shoulder 13

is best formed by a union 15 which connects the upper section 10' of the stem with the lower section.

The upper end of the stock 3 is cut out to form opposing ears 16 between which is fitted a cross bar 17 carrying at its middle a nut 18. The upper section 10' of the stem 60 10 is fitted through this nut with a thread 19 of great or long pitch, as shown. The upper end of the stem section 10' is formed or provided with a head 20 of any suitable character adapted to loosen the sand. 65

The use and advantages of my bailer will now be described, in connection with the removal of sand from a well.

Sand will sometimes, under the inrush of 70 gas or oil, heave up in the well several hundred feet and form a bridge. To try to break this bridge with a big and heavy string of drilling tools, will result, especially 75 if water be present, in making the sand pack tighter, or it may break the casing-pipe or it may part the sections of the casing string. The use of drilling tools for this purpose is obviated by my bailer. Again sand may get 80 into the well through the perforations in the casing and form a body therein, say, 100 feet high, to the level of the top perforations. It packs and fills the hole and the ordinary sand-pump will not lift it. If the drilling 85 tools be used to lighten it up, they are apt to break or spread the pipe, already weakened by the perforations. In this case, also, my bailer is intended to obviate the use of such tools.

When either a sand bridge or a pack of sand occurs, the drilling tools are lifted out of the hole, and my bailer is attached to the sand line and lowered into the well. In descending, the dart 9 hangs low by gravity 90 and the upper shoulder 13 of its stem pressing on the ball-valve 8 holds said valve to its seat 7, as is shown in Fig. 1. When the dart reaches the surface of the sand its descent is arrested, but the combined stock 3 95 and barrel 1 continuing their descent carry the nut 18 down the cork-screw like thread 19 of the dart stem section 10', the result of this relative lineal motion being that relative opposite axial rotation is imparted 100 to the dart and the stock and barrel; and as the stock and barrel are much heavier than the dart and not so free to rotate, it follows 105 that the rotation of the stock and barrel is negligible, while the main rotation, as is in- 110

tended, is imparted to the dart. This results in positively loosening the sand; and this operation may be made as gentle as desired, and thereby avoid all jarring, by 5 giving a short, quick reciprocation to the sand-line to lift and drop the bailer rapidly through a short distance. As the loosening of the sand is thus mainly dependent upon a rotation of the dart on its axis, it follows 10 that an auger-like form of said dart, such as I have shown, is of great advantage, in that both its penetration and its agitating qualities are of the best.

The feature of the ball-valve being freely 15 slidable upon the dart stem instead of, as is common in bailers of this class, being rigid on said stem, is of advantage in that the dart may be rotated repeatedly through a movement short of effecting contact of the 20 lower shoulder 11 with the valve, and, therefore, allowing the valve to remain closed until a sufficient volume of sand is loosened to warrant its passage into the barrel, whereupon a further or more pronounced 25 drop will effect the opening of the valve by the contact of the shoulder 11 therewith, and the charge will enter. Less sand will, therefore, drop back, than would fall out if the valve were rigid on the dart stem and 30 thus forced open at each movement of the dart.

When the bailer is full of sand it is lifted; and the weight of the dart and its stem will more positively effect, than will gravity 35 alone, the seating of the valve by the contact therewith of the upper stem shoulder 13. When the bailer reaches the surface, it is swung over into a box to dump its load. This is done by allowing its dart to strike 40 the bottom of the box, thereby lifting the valve. In my bailer, this dumping is facilitated by the turning of the dart stem on its axis, due to its contact with the bottom of the box, so that the head 20 of the stem, 45 working in the possibly packed sand within the bailer barrel, loosens it and thereby provides for its easy discharge.

I claim:—

1. A well-bailer comprising a barrel having 50 an admission check valve in its bottom; a dart projecting from and carried by the barrel bottom; and means dependent upon a relative lineal movement of the barrel and dart for rotating said dart on its axis.

55 2. A well-bailer comprising a barrel having an admission check valve in its bottom; an auger-like dart projecting from and carried by the barrel bottom; and means dependent upon a relative lineal movement of 60 the barrel and dart for rotating said dart on its axis.

3. A well-bailer comprising a barrel having 65 an admission check valve in its bottom; a dart projecting from the barrel bottom; and having a stem passing into the barrel

and slidable therein; and means dependent upon a relative lineal movement of the barrel and dart stem for rotating said dart on its axis.

4. A well-bailer comprising a barrel having 70 an admission check valve in its bottom; a dart projecting from the barrel bottom and having a stem passing into the barrel and slidable therein; and means dependent upon a relative lineal movement of the barrel and dart stem for rotating said dart on its axis, consisting of a fixed nut within the barrel bottom and a thread on the dart stem engaging said nut.

5. A well-bailer comprising a barrel having 80 an admission check valve in its bottom; a dart projecting from the barrel bottom and having a stem coacting with the valve to open and close said bottom; and means dependent upon a relative lineal movement 85 of the barrel and dart stem for rotating said dart on its axis.

6. A well-bailer comprising a barrel having 90 an admission check valve in its bottom; an auger-like dart projecting from the barrel bottom and having a stem coacting with the valve to open and close said bottom; and means dependent upon a relative lineal movement of the barrel and dart stem for rotating said dart on its axis.

7. A well-bailer comprising a barrel having 95 an admission check valve in its bottom; a dart projecting from the barrel bottom and having a stem passing into the barrel and coacting with the valve to open and close 100 said bottom; a fixed nut; and a thread on the dart stem engaging said nut, to rotate the dart upon its axis upon relative lineal movement of the barrel and dart stem.

8. A well-bailer comprising a barrel having 105 an admission check valve in its bottom; an auger-like dart projecting from the barrel bottom and having a stem passing into the barrel and coacting with the valve to open and close 110 said bottom; a fixed nut; and a thread on the dart stem engaging said nut, to rotate the dart upon its axis upon relative lineal movement of the barrel and dart stem.

9. A well-bailer comprising a barrel having 115 a valve seat in its bottom; an admission check valve for said seat; a dart projecting from the barrel bottom and having a stem passing into the barrel and slidable freely through the valve; upper and lower shoulders on the stem acting on the valve to close and open it; and means dependent upon a relative lineal movement of the barrel and dart stem for rotating said dart on its axis.

10. A well-bailer comprising a barrel having 120 a valve seat in its bottom; an admission check valve for said seat; an auger-like dart projecting from the barrel bottom and having a stem passing into the barrel and slidable freely through the valve; upper and lower shoulders on the stem acting on the 125 180

valve to close and open it; and means dependent upon a relative lineal movement of the barrel and dart stem for rotating said dart on its axis.

- 5 11. A well-bailer comprising a barrel having a valve seat in its bottom; an admission check valve for said seat; a dart projecting from the barrel bottom and having a stem passing into the barrel and slidale through 10 the valve; upper and lower shoulders on the stem acting on the valve to close and open it; and means dependent upon a relative lineal movement of the barrel and dart stem for rotating said dart on its axis, consisting of 15 a fixed nut, and a thread on the dart stem engaging said nut.
12. A well-bailer comprising a barrel having a valve seat in its bottom; an admission check valve for said seat; an auger-like dart 20 projecting from the barrel bottom and having a stem passing into the barrel and slidale freely through the valve; upper and lower shoulders on the stem acting on the valve to close and open it; and means dependent upon a relative lineal movement of the barrel and dart stem for rotating said dart on its axis, consisting of a fixed nut, 25 and a thread on the dart stem engaging said nut.
30. 13. A well-bailer comprising a barrel having an admission check valve in its bottom; a dart projecting from the barrel bottom and having a stem passing into the barrel and coacting with the valve to open and close 35 said bottom; a stirring head on the upper end of the dart-stem; and means dependent upon a relative lineal movement of the barrel and dart-stem for rotating the latter on its axis.
- 40 14. A well-bailer comprising a barrel; a hollow stock fitted to the lower end of the barrel, said stock having within it a valve-seat; an admission check valve for said seat; a dart projecting from the lower end of the 45 stock and having a stem passing into said stock and freely slidale through the valve;
- upper and lower shoulders on the stem acting on the valve to close and open it; a fixed nut carried by the upper end of the stock; and a thread on the dart-stem engaging said nut to rotate the dart upon its axis upon a relative lineal movement of the stock and dart-stem.
15. A well-bailer comprising a barrel; a hollow stock fitted to the lower end of the 55 barrel, said stock having a concaved shoe projecting from the barrel and having also an interior valve-seat; an admission check valve for said seat; a dart projecting from the lower end of the stock and having a 60 stem passing into said stock and freely slidale through the valve; upper and lower shoulders on the stem acting on the valve to close and open it; a fixed nut carried by the upper end of the stock; and a thread on the 65 dart-stem engaging said nut to rotate the dart upon its axis upon a relative lineal movement of the stock and dart-stem.
16. A well-bailer comprising a barrel; a hollow stock fitted to the lower end of the 70 barrel, said stock having a concaved shoe projecting from the barrel and having also an interior valve-seat; an admission check valve for said seat; a dart projecting from the lower end of the stock and having a 75 stem passing into said stock and freely slidale through the valve; upper and lower shoulders on the stem acting on the valve to close and open it; a stirring head on the upper end of the dart-stem; a fixed nut carried 80 by the upper end of the stock; and a thread on the dart-stem engaging said nut to rotate the dart upon its axis upon a relative lineal movement of the stock and dart-stem.

In testimony whereof I have signed my 85 name to this specification in the presence of two subscribing witnesses.
